DESIGN FOR A PACK FRAME

Asa J. Hartsock, Oakland, Calif.

Application January 23, 1941, Serial No. 98,298

Term of patent 14 years

To all whom it may concern:

Be it known that I, Asa J. Hartsock, a citizen of the United States and a resident of Oakland, county of Alameda, State of California, have invented a new, original, and ornamental Design for a Pack Frame, of which the following is a specification, reference being had to the accompanying drawing, forming part thereof.

Figure 1 is a perspective view of a pack frame showing my new design.

Figure 2 is an end view of the pack frame illustrated in Figure 1, the shoulder straps being omitted for convenience of illustration.

I claim:

The ornamental design for a pack frame, substantially as shown.

ASA J. HARTSOCK.
